UPWARDLY OPENING SAFE

Cecil T. Boughton, Canton, and Karl H. Miller,
North Canton, Ohio, assignors to Diebold Safe
& Lock Company, Canton, Ohio, a corporation
of Ohio

Application January 10, 1942, Serial No. 426,314

13 Claims. (Cl. 268—1)

The invention relates to upwardly opening safes, and more particularly to heat resisting safes including walls forming a compartment having an upwardly opening doorway, an upwardly opening door, and preferably elevator means actuated by the opening and closing of the door adapted for raising and lowering an article holder for valuables, usually documents such as record cards, record sheets, signature cards, and the like, from a position within the safe compartment when the door is closed to a position convenient for use above the safe compartment when the door is open, and for lowering the article holder and valuables back into the compartment upon closing the door.

Such a safe is set forth in United States Letters Patent No. 2,003,302 of William C. Miller and Albert L. Abbott for Safe structure, and the present invention includes improvements of the upwardly opening safe of said patent.

The door opening and closing means of said patent includes a fluid actuated vertically movable lift, the fluid actuating means for which includes a pair of hydraulic rams having cylinders mounting pistons whose upper ends are secured to the lift, a reservoir for the fluid, preferably oil, for operating the rams, a pump for drawing the oil from the reservoir and forcing the oil through conduits leading to the lower ends of the cylinders of the rams, an electric motor for operating the pump, and an electric circuit for operating the motor including a normally open starting switch, a normally open electro-magnetically controlled stick circuit switch, a normally closed stop switch, a normally closed limit switch, a normally open lock controlled switch, and when the safe contains file drawers, normally closed file drawer controlled switches.

In the safe of said patent, the electric motor drives the pump to pump the oil to the rams to cause the lift to elevate the door to the upper end of its movement in effecting either the opening or the closing of the door.

When the upper end of the door movement is reached the circuit of the motor is automatically interrupted by the limit switch after which the door lowers itself by gravity either to a position at the rear of the compartment when the safe is opened or to the closed position in the doorway.

As the lift lowers, the oil is forced out of the lower ends of the cylinders of the rams back through a regulator valve into the reservoir, the regulator valve including a variable opening for

controlling the rate of lowering or settling of the door.

Also, in said patent the lock controlled switch or circuit breaker is normally held open by the bolt work of the door locking mechanism until the bolt work is released to permit the door to be opened.

The normally open starting switch when momentarily closed, closes the circuit of the electro-magnetically controlled stick circuit switch. The normally closed stop switch operates to stop the motor at any instant by opening the stop switch. When file drawers are contained in the safe compartment, the drawer controlled switches therefor must all be closed before the motor can operate.

The general construction and arrangement and the operating characteristics of the safe of said patent have proven to be very satisfactory in use, but the fluid actuating means for the door lift are relatively difficult and expensive to manufacture, and are subject to operating difficulties usual with fluid actuated devices, such as clogging of the oil conduits by dust and dirt, excessive oil leakage past the pistons, unequal flow of oil to both rams with a consequent overloading of one ram, and the like.

The objects of the present invention include the provision of a safe having all the desirable characteristics of said U. S. Patent No. 2,003,302, and including electric motor driven mechanical actuating means for the vertically movable lift, the mechanical actuating means being of such nature as to enable more simplified and economical manufacture than the fluid actuating means for the lift of said patent, and being adapted for more satisfactory operation.

Further objects of the invention include the provision of an electric motor driven mechanical lift including a pair of raising and lowering members arranged for simultaneous equally distributed power raising and lowering.

Further objects of the present invention include the provision of an improved electric motor driven mechanical lift including two simultaneously operating raising and lowering members, and which is simplified in construction and in the arrangement and cooperation of its parts, so that the lift may be manufactured and maintained with facility and economy, and so that at the same time the lift is capable of operating with ease and certainty.

The foregoing and other objects are attained by the upwardly opening safe, and electric motor driven mechanical lift therefor, apparatus, parts, improvements, combinations, and sub-combinations,

tions, which comprise the present invention, and the nature of which is set forth in the following general statement, and preferred embodiments of which together with their mode of use are set forth in the following description, and which are particularly and distinctly pointed out and set forth in the appended claims forming part hereof.

The nature of the present invention may be stated in general terms as including walls forming a safe body having an upwardly opening doorway, a door arranged for guided movement to and from a fitting and closing position in the doorway, and improved lift means preferably hinge connected with one edge of the door for effecting raising and lowering movement of the door, the lift means including a pair of spaced mechanical jack means, preferably screw jack means, each jack means including a raising and lowering member preferably a rotary jack screw, a bridge extending lengthwise between the spaced jack means, and the bridge having ends secured to the raising and lowering members of the jack means. Preferably reversing electric motor drive means are located on the bridge, and preferably sprocket wheel and endless chain belt means providing a power drive connection between the electric motor drive means and the preferred rotary screw jack raising and lowering members of the jack means.

The improved safe furthermore preferably includes an improved electric circuit for controlling the operation of the motor, and also includes further improved details of construction and arrangement set forth hereinafter, and also preferably includes other parts as set forth in said U. S. Patent No. 2,003,302.

Preferred embodiments of the improvements are illustrated, by way of example, in the accompanying drawings forming part hereof, in which

Figure 1 is an isometric view of an upwardly opening safe including the improvements, with the hood removed of the improved electric motor driven mechanical lift, the lift being in its extreme lower position and the door hinge connected at its rear edge to the lift being in its closed position in the upwardly opening doorway;

Fig. 2, a similar isometric view, with the lift in an intermediate position between its extreme lower and upper positions and the door hinge connected to the lift in its concurrent intermediate position between its closed position and its extreme upper position;

Fig. 3, a top plan view of the safe, with its parts in their relative positions when the door is closed, and with the hood for the lift removed, as in Fig. 1;

Fig. 4, a rear vertical sectional view thereof as on line 4—4, Fig. 3, with the hood for the lift in place;

Fig. 5, a transverse sectional view thereof as on line 5—5, Fig. 3, with portions broken away and shown in section;

Fig. 6, a fragmentary transverse sectional view similar to Fig. 5, but showing the parts in their relative positions when the lift and the door are in intermediate positions, as shown in Fig. 2;

Fig. 7, a fragmentary view similar to Figs. 5 and 6, showing the parts in their relative positions when the lift and the door are in their extreme upper positions;

Fig. 8, a view similar to Figs. 5, 6, and 7, showing the parts in their relative positions when the lift and the door are in their extreme lower positions at the rear of the safe compartment, and with the article holder in its extreme upper posi-

tion, enabling access to and use of the articles contained in the article holder;

Fig. 9, a diagrammatic view illustrating the circuit of the electric motor driving the mechanical lift; and

Fig. 10, a fragmentary front elevation view showing the preferred lever operated stop switch for the drive motor of the safe, and the mounting of the stop switch on the safe body.

10 Similar numerals refer to similar parts throughout several views.

The improved upwardly opening safe is indicated generally by 10 and has an external appearance and many parts generally similar to or substantially the same as the safe illustrated in said U. S. Patent No. 2,003,302, and such parts will only be described briefly herein.

The illustrated safe 10 includes a composite safe body indicated generally by 10' and having an inner five-walled upwardly opening sheet metal compartment indicated generally by 11, and a five-walled monolithic heat and fire resisting shell indicated generally by 12 enclosing the inner compartment 11, the shell being provided with 15 tension reinforcing means indicated generally by 13, and the compartment and shell being enclosed in an external five-walled interlocking sheet metal case indicated generally by 14.

Each of the five-walled structures preferably 30 comprises five sides of a six-sided preferably rectangular polyhedron, the sixth upper side of which is open.

A door frame indicated generally by 15 connects the opening of the inner compartment 11 with the opening of the outer case 14 and forms a closure for the outer end of the monolithic shell 12. A door indicated generally by 16 forms a closure fitting the door frame, and the door and door frame are provided with usual interfitting tongues and grooves to form an effective flame and heat resisting joint between the door and the door frame when the door is in the closed position, and thus also providing a sealing closure for the upper sixth side of the composite safe body 10' and its compartment 11 and shell 12 and case 14.

The door 16 as illustrated includes an outer shell 18 of formed metal sheets, the interior of which is filled with heat resisting material 19 which is provided with tension reinforcing means 20.

A tray or article holder indicated generally by 21 is arranged for being lowered into and raised from the compartment 11 of the safe body 10', as shown by elevator means indicated generally by 22 operatively interposed between the article holder 21 and the safe body 10'. The article holder 21 and the elevator means 22 and their relationship with each other and the compartment 11 are substantially identical with those set forth in said U. S. Patent No. 2,003,302.

For the purposes of the present improvements, it need only be stated that the article holder 21 has mounted at each end thereof a pair of laterally spaced upwardly and downwardly extended articulated racks each indicated generally by 23.

Interposed between each end of the article holder 21 and the opposite end wall of the compartment 11, a horizontally extending shaft 24 has its forward end journaled in a suitable bearing 25 mounted in the front wall of the compartment 11, and the rear end of the shaft 24 extends through and is journaled in bearing means indicated generally by 26 extending

through the rear walls of the compartment 11, the shell 12, and the case 14.

On the shaft 24 within the compartment 11 a pair of pinions 27 are secured, each of which meshes with one of the articulated racks 23.

The composite safe body 10' as shown is supported upon a base frame indicated generally by 28, and a lift housing indicated generally by 29 is located at the rear of the safe body 10'.

Within the lift housing 29 the rear end of each shaft 24 has secured thereon a sprocket wheel 30.

The base frame 28 includes a rear wall 31 aligned with the rear wall of the case 14, and preferably vertically below each sprocket wheel 30, a sprocket wheel 32 is journaled on a bearing post 33 secured on the base frame rear wall 31.

An endless chain belt 34 extends about each set of vertically spaced sprocket wheels 32 and 30, and a horizontally extending elevator bar 35 is located in the housing 29 at the rear of the chain belts 34, and at each end the bar 35 is secured by a bracket 36 with the outer vertical line of links of one of the chain belts 34. The elevator bar 35 as shown is an angle bar having an upper horizontal flange at opposite ends of which above the brackets 36 are secured striker blocks 37 for contact with the lower edge of the door as it is being lowered into or raised from the housing 29, as hereinafter set forth in detail.

The article holder elevator means 22 of the present improvements is generally similar to but differs from the elevator means of said U. S. Patent No. 2,003,302 in the use of two separate chain belts 34 for the two sets of sprocket wheels 30 and 32 which operate the parallel horizontal shafts 24, whereas in said patent, an endless chain and bar linkage having central crossing portions are extended around and operate the similar sprocket wheels.

The operation of the elevator means 22 of the present improvements is the same as the operation of the elevator means of said patent, that is when the elevator bar 35 is lowered, the shafts 24 are rotated simultaneously. Assuming the article holder 21 to be in its lowermost position in the compartment 11, when the elevator bar 35 is lowered, the shafts 24 are rotated to raise the article holder 21, and vice versa.

On the outer top border of each end wall of the safe body 10', a forwardly and rearwardly extending track 40 is located, each track 40 being spaced endwise from the adjacent end edge of the door. At each front corner of the door, a bracket 41 mounts a cantilever stub shaft journaling a roller 42 rolling on the adjacent track 40. At each rear corner of the door 16 a hinge bracket 43 is secured.

The lift housing 29 has an open upper end and has operatively mounted therein improved lift means indicated generally by 44 which includes at each end of the housing 29 screw jack means indicated generally by 44' and including an upright jack tube 45 whose lower end preferably fits and is secured in and supported by a base socket 46 which in turn as shown is supported upon and secured within the bottom wall of a base pan 47 of the housing 29, the base pan 47 in turn as shown being supported upon a horizontal base plate 48 forming part of the base frame 28.

The housing 29 extends a substantial distance above the top of the safe body 10', and each jack

tube 45 terminates between the top of the housing 29 and the top of the safe body 10'.

At the upper end of each preferably cylindric jack tube 45 is secured a jack nut 49, and an elongated rotary jack screw 50 is screwed in each jack nut 49.

Each jack screw 50 has an upper shaft end 51 extending beyond the upper end of the threads of the jack screw and is mounted by a double thrust and journal bearing means indicated generally by 52 in a bracket and housing unit indicated generally by 53.

Each bracket and housing unit 53 includes a hinge bracket 54 extending vertically at one side of one of the hinge brackets 43 at one of the rear corners of the door 16, and each set of hinge brackets 43 and 54 are hinge connected with each other by a hinge pin 55 whose axis extends parallel with the rear longitudinal edge of the door 16 and is offset rearwardly therefrom in the usual manner.

Each bracket and housing unit 53 also includes a bridge bar connecting bracket 56 extending horizontally from the bottom of the one unit 53 towards the bracket 56 of the opposite unit 53 on the other jack screw 50.

A bridge bar 57 extends lengthwise between the bracket and housing units 53, and the ends of the bridge bar 57 are secured to the brackets 56 of the units 53 as by bolt and nut means 58.

The upper shaft end 51 of each jack screw 50 extends above its associated bracket and housing unit 53 within which it is bearing mounted, and above each unit 53 each jack screw shaft end 51 has a sprocket wheel 59 secured thereon.

As shown, centrally located on the bridge bar 57 is mounted a reversing electric drive motor and reduction gear unit indicated generally by 60 for the improved lift means 44.

The motor and reduction gear unit 60 includes a vertically extending drive shaft 61 having a pair of vertically spaced sprocket wheels 62 secured thereon, and each sprocket wheel 62 and one of the sprocket wheels 59 are operatively connected by an endless chain belt 63.

The improved lift means 44 furthermore includes a guide channel 64 located between each jack means 44' and the adjacent end wall of the housing 29, and the upper end of each guide channel 64 is secured to the bracket and housing unit 53 carried on the upper end of the screw of its associated jack means. The flanges of each guide channel 64 extend about its associated jack means towards the flanges of the other guide channel 64. At each end of the housing 29, walls form vertically extending slide guides 65 for each guide channel 64, and the improved lift means 44 is furthermore preferably reinforced by a rear plate 66 extending between and connected to the rear flanges of the guide channels 64.

Operatively associated with the safe body 10' and the lift housing 29, at each rear corner of the safe body 10', a track switch 67 is located including a forwardly opening groove track 68 having its front end aligned with one of the upper tracks 40 on the safe body 10'.

The groove track 68 communicates at its inner end with a vertical groove track 69 which also communicates with a rearwardly and downwardly extending groove track 70. A switch lever 71 is operatively mounted between the groove tracks 68 and 70 at the lower end of the vertical groove track 69 for automatic actuation by the associated roller 42 on the front edge of the door.

The lower end of each track groove 70 com-

municates with the upper end of a channel track 70' located in the housing 29.

Each track switch 67 is similar in construction and operation to the track switches of said U. S. Patent No. 2,003,302, and one of the track switches 67 is arranged for automatically actuating a reversing switch indicated diagrammatically in Fig. 9 in a manner similar to the operation of the limit switch of said patent.

In the safe 19, the door is provided with bolt work controlled by a combination lock indicated generally by 72, and the bolt work may be and preferably is associated with a lock controlled switch, as in said patent.

Likewise the safe 19 may be provided with drawer controlled switches when its article holder 21 is provided with drawers, as in said patent.

In the operation of the improved safe, when the article holder 21 is in the compartment 11 and the door 16 is closed as in Figs. 1, 3, 4, and 5, closing the normally open starting or raising switch 73 serves to operate the motor and reduction gear unit 60 and causes the sprocket wheels 62 and sprocket wheels 59 and their endless chain belt 63 to rotate the jack screws 50 in the stationary jack nuts 49 raising the jack screws and their bracket and housing units 53 hinge connected with the door 16, thereby raising the door 16 through the intermediate position shown in Figs. 2 and 6 to the extreme upper position of the jack screws and door, shown in Fig. 7, at which the reversing switch 74 is automatically actuated by one of the track switches 67 to cause reverse rotation of the motor 60 and lowering of the door 16 to its extreme lower position as shown in Fig. 8, the lowering of the door serving to actuate the elevator means 22 to raise the article holder 21 to the position for use shown in Fig. 8.

In the preferred wiring as shown diagrammatically in Fig. 9, the electric power supply line for the motor 60 includes two main conductors 75 and 76. As illustrated the conductor 76 extends to the central terminal 77 of the motor 60 through series connected switches, as follows: an overload circuit breaker 78, an emergency stop switch 79, and a plurality of drawer switches 80, the article holder 21 usually being provided with a plurality of drawers, as in U. S. Patent No. 2,003,302.

The other main power supply line 75 has a branch 75-1 which has series connected therein the starting or raising switch 73, the bolt work switch 81, the coil of the magnetic reversing relay 82 and a return therefrom to the line of the conductor 76 at a junction 83 beyond the drawer controlled switches 80.

The branch 75-1 has a second branch 75-2 in which is series connected one set of contacts 84 of the relay 82, the reversing switch 74 and the lowering switch 85 terminating in a junction at 86 with the branch 75-1 between the raising switch 73 and the lowering switch 85.

The main conductor 75 has another branch 75-3 which itself has one branch 75-4 in which is series connected another set of contacts 87 closed and opened simultaneously with the contacts 84 of the relay 82, the branch 75-4 extending from the contacts 87 to one outer terminal 88 of the motor 60, one of the motor windings being connected between the terminal 88 and the terminal 77.

Another branch 75-5 of the branch 75-3 of the main conductor 75 has series connected therein the set of contacts 89 of the relay 82 which are opened and closed reversely to the sets

of contacts 84 and 87, and from which the branch 75-5 extends to the other outer terminal 90 of the motor 60 with a stop switch 91 series connected therein.

5 In the diagram of Fig. 9, the various switches are shown in their positions when the door 16 is in closed position. Each of the drawer switches 80 and the bolt work switch 81 are safety switches and must be closed to permit raising of the door. 10 The drawer switches are closed when the drawers are closed, and the bolt work switch is closed when the bolt work is retracted.

The lowering switch 85 is normally closed, and 15 right hand rear corner of the safe body as viewed from the front, is closed except when held open by the actuator 92 secured on the right hand door hinge bracket 43.

The stop switch 91 has a downwardly extending 20 operating lever 93, and the actuator 92 has two actuating blades 94 and 95 at right angles to each other, one of which presses the lever 93 to hold open the stop switch 91 as and when the door 16 reaches either the fully closed or fully open position.

25 When the raising switch 73 is momentarily closed from its normally open position, the coil of the relay 82 is energized actuating its armature to close the sets of contacts 84 and 87 and to produce through contacts 84, and switches 74 and 85 another connection of one terminal of the relay coil with the main conductor 75, the other coil terminal being still connected to the main conductor 76, thereby continuing to energize the relay coil.

30 At the same time the conductor 75 is in a connected circuit through the relay contacts 87 with the motor terminal 88, and the main conductor 76 is in a connected circuit through the circuit breaker 78, the emergency stop switch 79, and the drawer switches 80 with the intermediate motor terminal 77, and the motor operates to raise the jack screws and door.

35 When the door 16 reaches its extreme upper position, the track switch 67 operates through the plunger 96, as set forth in U. S. Patent No. 2,003,302, to open the reverse switch 74, and de-energize the coil of the relay 82.

40 The relay armature returns to the position shown in Fig. 9, with the contacts 89 closed, and the stop switch 91 now being closed, the motor terminal 90 is connected with main conductor 75, and the motor terminal 77 still being connected with the main conductor 76, the motor reverses to lower the jack screws and door.

45 If the relay contacts should stick, the plunger 96 would continue downwardly and open the emergency stop switch 79, stopping the motor.

50 If during any raising movement of the screw jacks, it is desired to reverse the motor manually instead of automatically, the lowering switch 85 is momentarily opened, causing the relay coil to be deenergized, the relay armature to return to the reverse position, and the motor to reverse.

55 When the door nears and reaches the fully open position the actuating blade 94 opens and holds open the stop switch 91, and when the door reaches the fully closed position the actuating blade 95 opens and holds open the stop switch 91.

60 The use of the lever operated stop switch 91 alternately actuated by the blades 94 and 95 of the actuator 92 secured to the right hand door hinge bracket 43, permits the single stop switch 91 to be used for stopping the motor 60 as and when the door reaches both the fully open and fully

closed position, and also provides for coasting the motor since the blades 94 and 95 slide over the lever 93 of the stop switch 91 after having actuated the lever to open the stop switch 91.

When the door has reached its fully open position, and it is desired to close the door, the normally open starting or raising switch 73 is closed momentarily, and the door is automatically raised and lowered to the closing position, it being noted that for both opening the door and closing the door, the screw jacks first raise and then lower after the automatic actuation of the reverse switch 74 by the track switch 67.

The embodiments of the present improvements illustrated and described herein are by way of example, and the scope of the present invention is not limited to the same or to the particular details thereof, but is commensurate with any and all novel subject matter contained herein which may at any time properly under the United States patent laws be set forth in the claims hereof, or originating herein, and the elements of any such claims are intended to include their reasonable, functional and structural equivalents.

We claim:

1. In a safe and the like, a body having an inner compartment and an upwardly opening doorway for the compartment, a door arranged for guided movement to and from a closing position in the doorway, lift means having an operative connection with the door for effecting the guided movement of the door, the lift means including spaced mechanical jack means having raising and lowering members included in the operative connection of the lift means with the door, and electric motor drive means carried by the raising and lowering members for operating the jack means for simultaneously moving the raising and lowering members.

2. In a safe and the like, a body having an inner compartment and an upwardly opening doorway for the compartment, a door arranged for guided movement to and from a closing position in the doorway, lift means and hinge means operatively connecting the lift means with the door for effecting the guided movement of the door, the lift means including spaced mechanical jack means having raising and lowering members included in the hinge connection of the lift means with the door, and electric motor drive means carried by the raising and lowering members for operating the jack means for simultaneously moving the raising and lowering members.

3. In a safe and the like, a body having an inner compartment and an upwardly opening doorway for the compartment, a door arranged for guided movement to and from a closing position in the doorway, lift means having an operative connection with the door for effecting the guided movement of the door, the lift means including spaced mechanical jack means, each jack means including a raising and lowering member, a bridge extending lengthwise between the spaced jack means, the bridge having ends secured to the raising and lowering members of the jack means, an electric motor on the bridge, and power drive connecting means between the electric motor and the jack means for operating the jack means for simultaneously moving the raising and lowering members.

4. In a safe and the like, a body having an inner compartment and an upwardly opening doorway for the compartment, a door arranged for

guided movement to and from a closing position in the doorway, lift means and hinge connecting means between the lift means and the door for effecting the guided movement of the door, the lift means including spaced mechanical jack means, each jack means including a raising and lowering member, a bridge extending lengthwise between the spaced jack means, the bridge having ends secured to the raising and lowering members of the jack means, an electric motor on the bridge, and power drive connecting means between the electric motor and the jack means for operating the jack means for simultaneously moving the raising and lowering members.

5. In a safe and the like, a body having an inner compartment and an upwardly opening doorway for the compartment, a door arranged for guided movement to and from a closing position in the doorway, lift means having an operative connection with the door for effecting the guided movement of the door, the lift means including spaced screw jack means, each jack means including a raising and lowering rotary jack screw, each screw having journalled thereon a member included in the operative connection of the lift means with the door, and electric motor drive means carried by the journalled members for simultaneously rotating the jack screws.

6. In a safe and the like, a body having an inner compartment and an upwardly opening doorway for the compartment, a door arranged for guided movement to and from a closing position in the doorway, lift means and hinge connecting means between the lift means and the door for effecting the guided movement of the door, the lift means including spaced screw jack means, each jack means including a raising and lowering rotary jack screw, each screw having journalled thereon a member included in the hinge connecting means between the lift means and the door, and electric motor drive means carried by the journalled members for simultaneously rotating the jack screws.

45 7. In a safe and the like, a body having an inner compartment and an upwardly opening doorway for the compartment, a door arranged for guided movement to and from a closing position in the doorway, lift means having an operative connection with the door for effecting the guided movement of the door, the lift means including spaced screw jack means, each jack means including a raising and lowering rotary jack screw, each screw having journalled thereon a member included in the operative connection of the lift means with the door, a bridge extending lengthwise between the journalled members, the bridge having ends secured to the journalled members, an electric motor on the bridge, and power drive connecting means between the electric motor and the jack means for simultaneously rotating the jack screws.

65 8. In a safe and the like, a body having an inner compartment and an upwardly opening doorway for the compartment, a door arranged for guided movement to and from a closing position in the doorway, lift means and hinge connecting means between the lift means and the door for effecting the guided movement of the door, the lift means including spaced screw jack means, each jack means including a raising and lowering rotary jack screw, each screw having journalled thereon a member included in the hinge connecting means between the lift means and the door, a bridge extending lengthwise between the

journalled members, the bridge having ends secured to the journalled members, an electric motor on the bridge, and power drive connecting means between the electric motor and the jack means for simultaneously rotating the jack screws.

9. In a safe and the like, a body having an inner compartment and an upwardly opening doorway for the compartment, a door arranged for guided movement to and from a closing position in the doorway, lift means having an operative connection with the door for effecting the guided movement of the door, the lift means including spaced screw jack means, each jack means including a raising and lowering rotary jack screw, each screw having journalled thereon a member included in the operative connection of the lift means with the door, a bridge extending lengthwise between the journalled members, the bridge having ends secured to the journalled members, an electric motor on the bridge, and sprocket wheel and endless chain belt power drive connecting means between the electric motor and the jack means for simultaneously rotating the jack screws.

10. In a safe and the like, a body having an inner compartment and an upwardly opening doorway for the compartment, a door arranged for guided movement to and from a closing position in the doorway, lift means and hinge connecting means between the lift means and the door for effecting the guided movement of the door, the lift means including spaced screw jack means, each jack means including a raising and lowering rotary jack screw, each screw having journalled thereon a member included in the hinge connecting means between the lift means and the door, a bridge extending lengthwise between the journalled members, the bridge having ends secured to the journalled members, an electric motor on the bridge, and sprocket wheel and endless chain belt power drive connecting means between the electric motor and the jack means for simultaneously rotating the jack screws.

11. In a safe and the like, a body having an inner compartment and an upwardly opening

doorway for the compartment, a door arranged for guided movement to and from a closing position in the doorway, lift means having an operative connection with the door for effecting the guided movement of the door, the lift means including spaced mechanical jack means, each jack means including a raising and lowering member, a bridge extending lengthwise between the spaced jack means, the bridge having ends secured to the raising and lowering members of the jack means, an electric motor on the bridge, and power drive connecting means between the electric motor and the jack means for simultaneously moving the raising and lowering members, and slide guide means for the jack means, each slide guide means including a movable slide member secured to one of the raising and lowering members and an adjacent stationary guide member.

12. In a lift adapted for moving a guided door and the like to and from a closing position in an upwardly opening doorway of a compartment body and the like, spaced screw jack means, each jack means including a raising and lowering rotary jack screw, each screw having journalled thereon a member adapted for operative connection with the door and the like to be moved, and electric motor drive means carried by the journalled members for simultaneously rotating the jack screws.

13. In a lift adapted for moving a guided door and the like to and from a closing position in an upwardly opening doorway of a compartment body and the like, spaced screw jack means, each jack means including a raising and lowering rotary jack screw, each screw having journalled thereon a member adapted for operative connection with the door and the like to be moved, a bridge extending lengthwise and having ends secured to the journalled members, an electric motor on the bridge, and power drive connecting means between the electric motor and the jack means for simultaneously rotating the jack screws.
